RICHARD VON REPPERT, OF HARTFORD, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed September 23, 1927. Serial No. 221,451.

This invention relates to power-driven typewriting machines, and more specifically to that class of machines where power-driven electromagnetic forces are employed to drive the type-bars to a typing position following a partial depression of the associated key-levers.

The present invention is an improvement upon my pending application, filed September 15, 1927, Serial No. 219,607, where the semi-depression of a key-lever vibrates an armature, pivotally suspended therefrom to be shifted into the magnetic field of a constantly-rotating magnetized actuator, and, through the magnetic attraction or cohesion of the armature to the rotating actuator, completes the depression of the key-lever to a predetermined point where the magnetic control of the actuator is severed in advance of the typing movement, to free the key-lever which responds to the tension of its restoring spring. With driving means of this character, it is difficult for an operator, accustomed to manipulating the keys by a firm finger-stroke, to acquire the softer touch of manipulation for the semi-depression of the keys, where the softest touch of a key will immediately effect a clutching engagement with the rotating magnetized actuator, whereupon the key is withdrawn from under the operator's finger, and this results in the finger involuntarily following the key in its downward movement, and as a consequence the key's kick back results in a disagreeable shock to the finger.

The present invention includes a pivoted key-lever, a pivoted sub-lever having a positive driving connection with the type-bar, an intermediary member having a driving connection with the sub-lever, and an abutting or interrupted connection with the key-lever, through which connection a partial depression of the key-lever vibrates the intermediary member into the magnetic field of a power-driven, constantly-rotating, magnetized actuator where the magnetic attraction between the actuator and intermediary member will convey a driving movement to the sub-lever to drive the type bar; said intermediary member interrupting its magnetic

attraction with the magnetized actuator, by its throw to release the sub-lever to the restoring influence of its spring and effect the return of the type-bar and sub-lever after the typing of a character. Each key-lever is depressed to a fixed-stop position that is common to all the key-levers, and when so depressed vibrates the intermediary and not the sub-lever, and, hence, the burden of typing or the throwing of the type-bar to the platen is transferred wholly to the rotating magnetized actuator. The soft touch at the keys in partially depressing the key-levers against the positive stop enables the operator to more quickly withdraw the fingers from the depressed keys and the possibility of double typing is thereby avoided.

There may be times when it is desirable to actuate the type-carriers in the usual manner by the key-levers and not by the power-driven mechanism. In the present organization of the parts means are provided, which, by shifting of a key-lever stop-bar to an inoperative position, enable the key-levers to first vibrate the intermediary member against the stationary or inactive power-driving elements, and then manually depress the intermediary which becomes a key-actuated driver to the sub-lever; the key-lever, the intermediary and the sub-lever being depressed in unison by the finger-impact at the key, to drive the typing element to the typing position of the platen, and the down stroke of the key-lever being checked in the usual manner by the impact of the type-face against the platen and not by the stop-bar. The stop-bar in the present instance is pivotally supported and shiftable by a suitable finger-piece to operative or inoperative positions, thus providing a convertible control for the machine that instantly renders the machine operable for either a manual or a power-driven actuation of the typing elements.

A further improvement includes providing each intermediary member with electrical characteristics that become automatically effective at the end of a key-stroke to release the intermediary from the magnetic cohesive grip of the rotating actuator with a minimum of resistance, so that the separation or release

of the intermediary from the grip of the actuator will have no appreciable retarding effect upon the acquired inertia of the type-bar.

5 Other features and advantages will herein-after appear.

In the accompanying drawings,

Figure 1 is a centrally-vertical section from the front to the rear of an Underwood 10 typewriting machine, showing only such parts of the typewriter-mechanism necessary for cooperation with the power-driven actuator which form the subject-matter of this invention.

15 Figure 2 is an enlarged view, in perspective, of the extreme left-hand key of the keyboard and its connecting and operating parts that are co-operative with the power-driven magnetized actuator.

20 Figure 3 is a diagram of the electrical circuits, showing the electrical connections from the motor-circuit through the magnetized actuator.

Figure 4 is a partial front elevation in vertical section, the plane of the left-hand half 25 of the figure being taken between the two upper banks of the keys, and the plane of the right-hand half being taken just in front of the magnetized actuator.

30 Figure 5 is a reduced longitudinal section through the magnetic actuator, showing the relative engagement of the solenoid-sections and the manner of connecting the two end sections to the ring-commutator.

35 Figure 6 shows a key-lever depressed to its stop-position which operates to vibrate the intermediary into the magnetic field of the actuator without vibrating its sub-lever connected to the type-bar, the magnetic attraction from this point being effective to fully 40 vibrate the sub-lever to actuate its type-bar.

Figure 7 shows some of the parts of Figure 45 6 drawn downwardly to a point where the sub-lever has reached the end of its stroke and the intermediary is about to respond to its restoring spring which withdraws the intermediary from the magnetic control of the actuator and permits both sub-lever and type-bar to be restored to their normal positions.

50 Figure 8 is a modified form of key-controlled connections to vibrate an intermediary member or armature into the magnetic field of the actuator to effect the depression of a sub-lever operatively connected to throw a 55 type-bar to type, which, for the compact assembly thereof, renders the magnetic power-driving features applicable to machines having many banks of keys, as in double keyboard typewriting machines, where each key 60 operates a type-bar having only a single type-face.

Numeral and alphabet keys 10 and 11, when depressed, operate key-levers 12, which, instead of being fulcrumed upon the fulcrum- 65 rod in the usual manner, are individually ful-

crumed at 13 to the rear end of levers 14, fulcrumed as a series upon a stationary rod 15. Each lever 14 has a pin-and-slot driving connection 16 to vibrate a bell-crank 17 about a fulcrum-rod 18 to drive a type-bar 19 upwardly and rearwardly against the platen 20, rotatably mounted within a carriage 21 traveling upon carriage-rails 22 and 23 under the influence of a carriage-motor 24 and controlled by a step-by-step carriage-feeding 70 mechanism 25, operated by a universal bar 26, vibrated by each type-bar in typing. The levers 12 and 14 may have individual springs 27 and 28 for restoring each lever independently of the other. From this description it

75 will be noted that each type-bar has a pair of depressible pivoted levers arranged side by side, one lever having a key and no driving connections with the type-bar, and the other lever having no key, but having driving connections to the type-bar, and the latter will be designated hereinafter as sub-levers or a type-bar driving lever. To establish typing co-operation between these two levers 12 and 14, the forward end of each sub-lever may be 80 formed with a downward extension 29, provided with an adjustable saddle 30, pivotally supporting an interponent or intermediary member 31, having a short arm 32 to engage the under edge of the key-lever 12, and further provided with a downwardly-extending arm 33 formed with a section 34 bent over at right angles to present a wide flat face.

85 The series of intermediary members may be held in vertical alignment, when vibrated by their key-levers, by a suitable comb 35, and a working alignment of the intermediary members with the key-levers will be further secured by a comb 36 at the front end of the key-levers. Each intermediary member 31 is normally held within the comb 35 under 90 the tension of a spring 35^a which has a comparatively light tension to permit the vibration of the intermediary member without vibrating the associated sub-lever 14, and the tension of each key-lever spring 27 is also 95 proportionately light, so that only a very light touch of the finger is required to manipulate the machine.

100 To limit the depression of the key-levers and provide a positive stop-rest for the operator's fingers in typing, a rock-shaft 37, having a bearing in each side wall of the machine-frame, is provided with a stop-bar 38, the upper edge thereof underlying all the 105 key-levers.

110 The intermediary member 31 may be formed from soft sheet iron having the electrical properties of an armature to be attracted by a magnetized body, which body, in the present instance, includes a series of coils, assembled end to end and enclosed within the metallic sections that take a cylindrical form to become a rotating permanently magnetizable actuator for the intermediary 115 120 125

members, as fully described in my pending application before mentioned. The coils 39, Figure 5, are enclosed by metal sections 40 and alternate coils may be wound and assembled on the shaft 41 for opposite polarities and the series of sections 40 maintained upon the shaft 41 between suitable heads 42 secured to the shaft. The terminals 43 of each end coil of the series are connected to commutator-rings 44, insulated from the heads 42 and provided with a brush 45 secured to an insulator-support 46 on the side frames of the machine. To drive the shaft 41, one end thereof may carry a worm-gear 47, driven by a worm 48, secured to a shaft 49 of an electric motor 50. The circuit of the motor may be tapped to carry an electric current through a variable resistance 51 to the two brushes 45, so that whenever the motor-control switch 52 is closed to start the motor, the current will pass through coils 39 and the sections 40 will become continuously magnetized during the interval the motor is active in rotating the coils. The shaft 41 and sectional cylinder 53 may be suspended from arms 54, secured to a rock-shaft 55 to form a rockable frame or cradle that is adjustable as a unit through set-screws 56 to raise or lower the horizontal axis of the magnetic coils of the cylinder relative to the armatures 31.

The description up to this point provides that the depression of a key-lever 12 against the stop-bar 38 vibrates the armature or intermediary member into the magnetic field of the cylindrical actuator, which, through magnetic attraction, promotes a cohesive grip upon the armature, and the rotating face of the actuator causes the armature to roll downwardly to exert a down pull at the forward end of the sub-lever 14 to vibrate the bell-crank 17 and throw the type-bar 19 to type.

In my pending application, the armature carries a non-magnetic cam that becomes operative by the throw of the armature to wedge itself between the cylinder and the armature and forcibly separate the latter from the former, to sever the magnetic control of the armature from the cylinder. As this camming effect must be accomplished by the inertia of the typing elements to type, this camming-off operation may have a retarding effect upon the type-bars and slow down the speed of the machine. To overcome such defects, should they be found to exist, the non-magnetic cam is replaced by a non-magnetic flat-face section 57 as a continuation of the flat face 34 of the armature, so that the face of the cylinder 53 will roll from the magnetic section 34 upon the non-magnetic section 57 with no appreciable magnetic resistance from the cylinder and no retarding effect upon the acquired momentum of the sub-lever and type-bar.

When a key-lever is depressed to the position of Figure 6, the lever is arrested by the stop-bar 38 and the face of the section 34 of the intermediary member or armature 31 is vibrated against the face of the magnetized cylinder 53. Should the key-lever have a further depression, it is obvious that if the cylinder 53 is stationary, and consequently demagnetized, the section 34 would become a shoe to slide over the face of the cylinder and the key in depressing the intermediary member effects the manual depression of the sub-lever 14 to actuate the type-bar. Hence, by shifting the stop-bar at will, means are provided for operating the typing elements manually by the keys or by a power-driven means conditioned by a semi-depression of the keys.

To this end, the rock-shaft 37 may be provided at one end with a control arm 58, swingable to the inoperative dotted position of Figure 1 to provide for a full typing depression of the key-levers, and said bar may be held in either position by a flat spring 59 bearing against flat spots on the shaft 37.

As a possible modification of the present invention, the power-actuating means may be applied to a double keyboard machine where each key operates a type-bar having a single type-face, and where the usual power-driving mechanism cannot be applied to the closely-banked connections to the type-bars of a visible-writing front-strike machine. As shown in Figure 8, eight banks of keys, as 10^a, may be mounted upon key-stems 60, having their lower ends pivotally secured to arms of bell-cranks 61, arranged to vibrate upon stationary rods 62. Depression of the keys vibrates the bell-cranks 61, having connections at their lower ends to the typing elements after the manner of well-known styles of typewriters. For purposes of the present organization of parts, the lower arm of each bell-crank 61 is pivotally connected to the forward end of a push bar 63, guided horizontally through a comb 64 and having a stop-face 65 to normally engage the face of said comb under the tension of a spring 66. The free end 67 of the push bar 63 is aligned to engage with an intermediary member 68, pivotally connected to the sub-lever 14 in a manner already described. The depression of a key 10^a slides the bar 63 through the comb 64 and pushes the intermediary member 68 into the field of the rotary magnetized cylinder 53, the depression of the key being limited by a stop-face 69 striking the comb 64, and the intermediary member separating itself by its throw from the magnetic cohesion of the cylinder, as previously described, through the non-magnetic member 57. These simple connections of thin flat metal can readily be assembled within a frame having a standard machine width and eight or more banks of keys.

120
125
130

It will be noted that the semi-depression of the keys is limited by a fixed stop which is 5 restful to the fingers of the operator and enables the operator to more quickly remove the fingers from the depressed keys; that the pendent armature or intermediary member, having a flat face composed of magnetic and non-magnetic properties or characteristics, will roll through the horizontal magnetic axis 10 of the rotating solenoid until the restoring spring of the intermediary member overcomes the quickly diminishing magnetic forces of the solenoid and without any appreciable opposition to the momentum of said intermediary member and its connected parts 15 in typing; and that the rocking of the saddle 30 upon the lever-extension 29, by suitable set-screws, raises or lowers the normal position of the armature 33 and adjusts the relative position of the non-magnetic section 57 thereof to the magnetic cylinder 53, to regulate the extent of magnetic depression of the armature and type-bar lever to the throw of the type-bar.

25 Variations may be resorted to within the scope of the invention, and portions of the improvements may be used without others.

Having thus described my invention, I claim:

30 1. In a typewriting machine, the combination of a constantly-rotating, electromagnetized actuator for a typing mechanism that includes a lever having a positive driving connection with a type-bar, a key-lever, and 35 means carried by the type-bar-lever and operated directly by the key-lever, to magnetically connect said type-bar-lever with the magnetized actuator, to drive the type-bar by the magnetic attraction or cohesion with said 40 means.

45 2. In a typewriting machine, the combination of a constantly-rotating, electromagnetized actuator for a typing mechanism that includes a lever having a positive driving connection with a type-bar, a key-lever, and an intermediary member having a pivotal connection with the type-bar-lever and operated directly by the key-lever, to magnetically connect said type-bar-lever with the magnetized actuator, to drive the type-bar by the magnetic attraction or cohesion with said 50 intermediary member.

55 3. In a typewriting machine, the combination of a constantly-rotating, electromagnetized actuator for a typing mechanism that includes a lever having a positive driving connection with a type-bar, a key-lever, and a bell-crank-member pivotally secured to the type-bar-lever and having one arm operated 60 directly by the key-lever to vibrate another arm that magnetically connects said type-bar-lever with the magnetized actuator, to drive the type-bar by the magnetic attraction or cohesion with said bell-crank-member.

65 4. In a typewriting machine, the combina-

tion of a constantly-rotating, electromagnetized actuator for a typing mechanism that includes a lever having a positive driving connection with a type-bar, a key-lever normally inoperative to type, and means having a driving connection with the type-bar-lever and an interruptive connection with the key-lever, whereby said means may be presented to the rotating actuator, to drive the type-bar by magnetic attraction.

70 5. In a typewriting machine, the combination of a constantly-rotating, electromagnetized cylinder, a lever having a positive driving connection with a type-bar, a key-lever, and an armature having a driving connection with the type-bar-lever and operated by the key-lever, said armature having a flat face engageable with the face of the rotating cylinder to drive the type-bar with a maximum of magnetic attraction.

75 6. In a typewriting machine, the combination of a constantly-rotating, electromagnetized actuator for a typing mechanism that includes a lever having a positive driving connection with a type-bar, a key-lever, an armature-member carried by the type-bar-lever and operated directly by the key-lever to swing into rolling contact with the rotating actuator and drive the type-bar by the magnetic attraction or cohesion with said armature-member, and means carried by said armature-member that become effective during the rolling contact thereof with the actuator to type, to release said armature-member from the magnetic grip of the actuator to restore the type-bar.

80 7. In a typewriting machine, the combination of a constantly-rotating, electromagnetized actuator for a typing mechanism that includes a lever having a positive driving connection with a type-bar, a key-lever, an armature-member carried by the type-bar-lever and operated directly by the key-lever to swing into rolling contact with the rotating actuator and drive the type-bar by the magnetic attraction or cohesion with said armature-member, and means carried by the armature-member that become effective during the continuous rolling contact thereof with the actuator to type, to release said armature-member from the magnetic grip of the actuator to restore the type-bar, said means including a non-magnetic section of the armature-member that rolls into the magnetic field of the actuator.

85 8. In a typewriting machine, the combination with a type-bar having a compressible driving lever connected thereto, a pivoted key-lever, and a power-driven, continuously-rotating, magnetized cylinder, of means connected to the type-bar-driving lever and shiftable by the depression of the key-lever into the magnetic field of the cylinder to actuate said type-bar-lever to type.

90 9. In a typewriting machine, the combina-

tion with a type-bar having a depressible driving lever connected thereto, a pivoted key-lever, and a power-driven, continuously-rotating, magnetized cylinder, of means having a driving connection with the type-bar-lever and shiftable by the depression of the key-lever, said means, when so shifted by the key-lever, first responding to the magnetic attraction of the cylinder to be subsequently driven by the cylinder to actuate the type-bar.

10. In a typewriting machine, the combination with a type-bar having a depressible driving lever connected thereto, a pivoted key-lever, and a power-driven, continuously-rotating, magnetized cylinder, of means having a driving connection with the type-bar-lever and shiftable by the depression of the key-lever, said means, when so shifted by the key-lever, first responding to the magnetic attraction of the cylinder and then driven by the cylinder to actuate the type-bar, said means having electrical characteristics operative at a predetermined point of its throw to 20 cut off said means from the control of the cylinder to restore the type-bar lever.

11. In a typewriting machine, the combination with a type-bar having a depressible driving lever connected thereto, a pivoted key-lever, and a power-driven, continuously-rotating, magnetized cylinder, of means having a driving connection with the type-bar-lever and shiftable by the depression of the key-lever said means, when so shifted by the key-lever, first responding to the magnetic attraction of the cylinder and then driven by the cylinder to actuate the type-bar, said means including a section having non-magnetic properties that nullify the magnetic effect of the cylinder and release the type-bar-lever at the end of its typing movement.

12. In a typewriting machine, the combination of a power-driven, magnetized driver operative through its magnetism to 45 drive the type-bars in typing, levers having driving connections with the type-bars, one lever for each type-bar, a magnetic pendent for each lever that normally is spring-pressed out of the range of said magnetic driver, and 50 manual means to vibrate each pendent into the magnetic grip of the driver to actuate the lever and drive the type-bar, said means including a key-lever having an interrupted depression and an interruptive connection with the pendent.

13. In a typewriting machine, the combination of a power-driven, magnetized driver operative through its magnetism to drive the type-bars in typing, levers having driving 60 connections with the type-bars, one lever for each type-bar, a magnetic pendent for each lever that normally is spring-pressed out of the range of said magnetic driver, and manual means to vibrate each pendent into the 65 magnetic grip of the driver to actuate the

lever and drive the type-bar, said means including a pivoted key-lever having a limited depression and an abutting one-way connection with the pendent.

14. In a typewriting machine, the combination of a power-driven, magnetized driver operative through its magnetism to drive the type-bars in typing, levers having driving connections with the type-bars, one lever for each type-bar, a magnetic pendent for each lever that normally is spring-pressed out of the range of said magnetic driver, and manual means to vibrate each pendent into the magnetic grip of the driver to actuate the lever and drive the type-bar, said means including a pivoted key-lever having a limited depression and an abutting one-way connection with the pendent, and a stop-bar common to all the key-levers, to limit the manual depression thereof in vibrating the pends.

15. In a typewriting machine, the combination of a typing mechanism including a type-bar-actuating lever and a disconnected key-lever, a power-driven, constantly-rotating, magnetized cylinder, and a magnetic clutch-member having a driving connection with the type-bar-actuating lever and an interruptive connection with the key-lever, whereby said clutch-member, when vibrated by the key-lever into magnetic clutching engagement with the cylinder, will be driven by said cylinder to actuate the type-bar independently of the key-lever.

16. In a typewriting machine, the combination of a typing mechanism including a type-bar-actuating lever and a disconnected key-lever, a power-driven, constantly-rotating, magnetized cylinder, and a magnetic clutch-member having a driving connection with the type-bar-actuating lever and positioned to be vibrated by the key-lever into clutching engagement with the magnetized cylinder, said clutch-member automatically separating itself from the magnetic clutch of the cylinder at the end of the typing movement by its throw.

17. In a typewriting machine, the combination of a typing mechanism including a sub-lever operatively connected to vibrate a type-bar and a key-lever disconnected from the typing mechanism, an intermediary member having a driving connection with the sub-lever and a depressible connection with the key-lever, and a power-driven, electromagnetized, rotating body, said intermediary member, when presented to the magnetic cohesive forces of said rotating body by the depression of the key, will be operative to vibrate the sub-lever and actuate the type-bar to type.

18. In a typewriting machine, the combination of type-bars, levers positively connected to drive the type-bars, a universal, power-driven, rotatable electromagnetized

driver, interponents connected to the type-bar-levers and normally out of the magnetic field of the driver, and pivoted key-levers operable to selectively bring the interponents into the magnetic control of the driver, to actuate the type-bar-driving levers independently of the key-levers.

19. In a typewriting machine, the combination of a series of segmental type-bars, a series of horizontally-disposed levers positively connected to drive the type-bars, one lever for each type-bar, a series of vertically-disposed couplers, one coupler hanging pendent from each type-bar-lever, a power-driven, electromagnetized driver common to all the couplers, and a series of horizontally-disposed, pivoted key-levers, one key-lever aligned to each coupler and each key-lever operative when fully depressed to selectively 20 vibrate a coupler into the magnetic control of the driver, to actuate the associated type-bar-driving lever.

20. In a typewriting machine, the combination of a power-driven, constantly-rotating, electromagnetized cylinder operative through magnetic cohesion to drive the type-bars in typing, a pair of levers for each type-bar, one lever having a driving connection to the type-bar, and the other lever pivoted to 25 the first lever and having a key, and an intermediary member pivotally secured to the type-bar driving lever to be vibrated by the depression of the key-lever into the magnetic field of the rotating cylinder, to be magnetically attached thereto to drive the type-bar,

21. In a typewriting machine, the combination of a power-driven, constantly-rotating, electromagnetized cylinder operative through magnetic cohesion to drive the type-bars in 40 typing, a pair of independently-depressible levers for each type-bar, one lever of each pair having a positive driving connection with a type-bar, and the other lever having a manually-depressible key, an intermediary member having a pivotal connection to the type-bar-driving lever and swingable by the depression of the key-lever into the magnetic field of the rotating cylinder to be magnetically attached thereto to drive the type-bar, 45 and a stop-bar to limit the depression of all the key-levers to the swing of the intermediary to the cylinder.

22. In a typewriting machine, the combination of a type-bar mechanism including a type-bar-actuating lever and a disconnected key-lever, a power-driven cylinder operative at will to be rotatably magnetized or to be stationary and demagnetized, an intermediary member having a driving connection 55 with the type-bar-actuating lever and an interruptive connection with the key-lever, whereby said intermediary member may be vibrated by the key-lever into the magnetized field of the cylinder to be power-actuated, or 60 vibrated and depressed by the key-lever to 65

manually actuate the type-bar-lever when the power-cylinder is stationary and demagnetized, and stop means operative to predetermine the depression of the key for either a manual or power actuation of the intermediary member.

23. In a typewriting machine, the combination with a type-bar, having a depressible driving lever connected thereto, a disconnected key-lever and a power-driven continuously-rotating magnetic cylinder, of a pendant connected to the type-bar driving lever and shiftable by the depression of the key-lever into the magnetic field of the cylinder to depress said type-bar lever for a fixed throw of the type-bar in typing, and means to regulate the magnetic depression of the type-bar lever to the throw of the type-bar.

24. In a typewriting machine, the combination with a type-bar, having a depressible driving lever connected thereto, a disconnected key-lever and a power-driven continuously-rotating magnetic cylinder, of a pendant connected to the type-bar driving lever and shiftable by the depression of the key-lever into the magnetic field of the cylinder to depress said type-bar lever for a fixed throw of the type-bar in typing, and means to regulate the magnetic depression of the type-bar lever to the throw of the type-bar, said regulating means including a hanger adjustably secured to the type-bar driving lever to pivotally support said pendant.

25. In a typewriting machine, the combination with a type-bar, having a depressible driving lever connected thereto, a disconnected key-lever and a power-driven continuously-rotating magnetic cylinder, of a pendant connected to the type-bar driving lever and shiftable by the depression of the key-lever into the magnetic field of the cylinder to depress said type-bar lever for a fixed throw of the type-bar in typing, and means to regulate the magnetic depression of the type-bar lever to the throw of the type-bar, said regulating means including a hanger rockably mounted upon the type-bar driving lever to pivotally support said pendant and raise and lower said pendant to the magnetic axis of the cylinder.

RICHARD VON REPPERT.
